(57) **CLAIM**

We claim the ornamental design for a pet bed, as shown and described.

DESCRIPTION

FIG. 1 is a top right perspective view of an embodiment of a pet bed showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a cross section elevational view of an interior portion of FIG. 1 taken along line 7-7 shown in FIG. 6;

FIG. 8 is a cross section elevational view of an interior portion of FIG. 1 taken along line 8-8 shown in FIG. 6;

FIG. 9 is a cross section elevational view of an interior portion of FIG. 1 taken along line 9-9 shown in FIG. 6; and,

FIG. 10 is a cross section elevational view of an interior portion of FIG. 1 taken along line 10-10 shown in FIG. 6.

The broken lines shown herein depict environmental subject matter and form no part of the claimed design. The bottom of the pet bed is flat and devoid of ornamentation.

1 Claim, 7 Drawing Sheets
